UNITED STATES PATENT OFFICE.

JOHN C. PARTTRIDG, OF OKLAHOMA, OKLAHOMA.

DOOR FRAME AND HINGE.

Application filed February 14, 1921. Serial No. 444,836.

To all whom it may concern:

Be it known that I, JOHN C. PARTTRIDG, a citizen of the United States, residing at Oklahoma city, in the county of Oklahoma and State of Oklahoma, have invented certain new and useful Improvements in Door Frames and Hinges; and I do hereby declare the following to be a full, clear, and exact description of the invention, such as 10 will enable others skilled in the art to which it appertains to make and use the same.

The invention relates to swinging closures such as doors for barns and like structures, the purpose being to provide a frame independent of the structure for carrying the 15 weight of the door and which is adjustable to insure a neat fit, said frame, besides bearing the weight of the door, serving as bracing means for the barn or like structure.

20 A further purpose of the invention is the provision of a hinge of peculiar formation and capable of lifting the door as the latter swings so as to clear any obstruction tending to interfere with the free swinging 25 of the door.

Other objects and advantages will be apparent and suggest themselves as the nature of the invention is understood.

While the drawings illustrate an embodiment of the invention, it is to be understood that in adapting the same to meet different conditions and requirements, various changes in the form, proportion and minor 30 details of construction may be resorted to 35 without departing from the nature of the invention.

Referring to the accompanying drawings forming a part of the specification,

Figure 1 is a front view of a barn showing 40 the application of the invention,

Figure 2 is a detail view of the adjustable joint between the sections of the frame,

Figure 3 is a detail view of the hinge,

Figure 4 is a detail view of a modified 45 form of the hinge having a removable cap plate,

Figure 5 is a transverse sectional view through fragments of a closure and building illustrating the improved hinge connection 50 employed in plan.

Figure 6 is a detail view of one form of foot for the frame, and

Figure 7 is a detail view of another form of foot for the frame.

55 Corresponding and like parts are referred

to in the following description and designated in the several views of the drawings by like reference characters.

The numeral 1 designates a barn or like structure provided with a door opening 60 which is closed by means of a door mounted in accordance with the present invention. A frame 2 surrounds the door opening and is practically independent of the barn or like structure. The door, or doors, is hinged 65 directly to the frame, the latter carrying the weight and serving as bracing and reinforcing means for the structure. The frame 2 comprises similar or like sections which are adjustably connected, whereby provision is 70 had for maintaining a close joint between the parts comprising the door closure. Each section or part of the frame 2 comprises an upright portion and a horizontal portion. The upright portions of the frame are preferably stepped in concrete 3 which forms a 75 footing therefor. Any suitable means may be employed for insuring and maintaining a positive connection between the frame and the concrete footing 3. As indicated in Figure 6, a bar or strap 4 is embedded in the concrete 3 and the lower end of the frame 2 engages the part 4 in any convenient way. As illustrated in Figure 7, a plate 5 receives the lower end of the frame which is threaded 80 thereto, said plate being secured to the concrete by means of bolts 6, or analogous fastening means.

85 A coupling 7 adjustably connects the horizontal portions of the frame. The opposite ends of the coupling 7 are reversely threaded and engage correspondingly threaded ends of the frame. The intermediate portion of the coupling 7 is constructed to receive a suitable tool, whereby the coupling may be 90 rotated to effect adjustment of the frame. As shown, the intermediate portion of the coupling is of polygonal form to receive a wrench or spanner. A bracket 8 is secured 95 in any convenient and substantial way to 100 the barn or structure 1 centrally of the door opening, and its end portions are adjustably connected to the horizontal portions of the frame beyond the joint formed by the coupling 7. Bolts 9 secure the horizontal 105 portions of the frame to opposite ends of the bracket 8 and pass through slots 10 formed in the end portions of the bracket. When adjusting the frame, the bolts 9 are loosened and, after adjustment has been effected, the 110

frame is made secure in the adjusted position by retightening the bolts 9, as will be readily understood.

The hinges comprise bars 11 and movable leaves 12. The pintle ends of the bars 11 are forked to receive the pintle ends of the leaves 12. Bars 11 are secured to the barn or structure 1. Leaves 12 are attached to the door or closure 13. The hinge or pintle ends of bars 11 and leaves 12 are formed with leaves or eyes through which the upright portions of the frame 2 pass. Leaves 12 are thus journaled to swing laterally on the frame 2. The eye ends of the hinge members may be of any construction. In some instances it may be preferable to provide removable cap plates 14 whereby the parts may be easily assembled and provision had for ready dismemberment of the parts when required. A screw thread connection 15 is provided between the frame 2 and the hinge member 12 to admit of lifting the door simultaneously with its swinging movement, thereby enabling the door to clear an obstruction when swinging into open position. The screw threads constituting the screw thread connection 15 may be of any form and relative pitch. The forked members of the part 11 must be separated a distance to provide ample space for the vertical movement of the hinge member 12. The frame 2 is preferably tubular and constructed of pipes, the sections being connected by the usual pipe fittings. The hinge member 11 secured to the barn 1 is made fast to the frame 2. The hinge member 12 is loose so as to swing freely about the upright portion of the frame 2. When the hinge embodies a screw thread connection, as 15, a coupling member 16 is provided and its end portions are slipped into the sections of the upright portion of the frame and are pinned or otherwise secured thereto. The intermediate portion of the coupling member 16 is provided with screw threads forming the screw thread connection between the frame and hinge member 12. This arrangement provides for the ready assembling of the parts and for replacement when repairs become necessary.

The frame 2, to which the doors or closures are hinged, is practically independent of the structure, since it is not built in as a part thereof. The frame 2 may be secured to the structure opposite the door opening in any manner so as to materially assist in reinforcing and bracing the same. The entire

weight of the doors or closures is carried by the frame 2, thereby relieving the structure of the usual stresses incident to hinging the doors directly thereto. By having the frame 2 adjustable, a neat fit may be maintained since the frame may be expanded to allow for swelling or contracted to compensate for shrinkage. The lifting of the door simultaneously with its swinging into open position provides for free movement and prevents the hanging of the door on the surface as commonly experienced in the operation of swinging barn doors.

What is claimed is:

1. A barn or like structure provided with a door opening, a frame comprising upright portions and horizontal portions, a footing as concrete receiving the upright portions of the frame, means adjustably connecting the horizontal portions of the frame, a closure for the door opening, and hinge members mounted on the frame and having connection with the structure and closure, respectively.

2. In combination, a barn or like structure having a door opening, a frame in line with the door opening and comprising upright portions and horizontal portions, a bracket secured to the structure above the door opening, means adjustably connecting the horizontal portion of the frame with said bracket, coupling means adjustably connecting the horizontal portions of the frame, and closure means hingedly connected to the upright portions of the frame.

3. A barn or like structure having a door opening, a frame in line with the door opening and comprising upright portions and horizontal portions, a footing receiving the upright portions of the frame, a coupling adjustably connecting the horizontal portions of the frame, a bracket secured to the structure above the door opening and having adjustable connection with the horizontal portions of the frame, a closure, and hinge connections between the upright portions of the frame and closure comprising cooperating fixed and movable threaded members whereby to effect vertical movement of the closure simultaneously with its swinging movement.

In testimony whereof I affix my signature in presence of two witnesses.

JOHN C. PARTTRIDG.

Witnesses:

JOHN W. SHIELDS,
R. H. ELKINS.
